COTTON PICKING SYSTEM AND AIR FILTER
FOR USE IN SAMERobert S. Curley, Lowell, Mass., assignor to Saco-
Lowell Shops, Boston, Mass., a corporation of
Massachusetts

Application April 4, 1932, Serial No. 603,032

9 Claims. (Cl. 19—88)

It is customary in a picker room to draw air from the room into the beaters and condensers of the picking machines and to discharge the dust laden air into a dust room or at some point outside the building. In a typical picker installation approximately fifteen hundred cubic feet of air are delivered per minute from a single beater or condenser. Consequently, in cold weather the loss of heat from this cause alone is a very substantial item. Furthermore, while picker rooms are not usually humidified, it is very desirable that they should be. This fact is now gaining recognition, but it is not feasible to humidify picker rooms with the present condensing and dust handling systems.

The present invention deals especially with these conditions. It aims to devise a thoroughly practical arrangement for removing the dust from the air stream discharged from any condenser, beater, or pneumatic cotton conveying apparatus while conserving its heat and moisture content, and at the same time preventing the creation of any serious resistance to the flow of air.

It is a fairly common experience in mills to have a fire in the dust room, such fires occur usually being caused by the presence of matches, pieces of metal, or some foreign material in the cotton fed to the beaters. Fires originating in this manner sometimes assume very serious proportions and it is one of the objects of this invention to reduce the fire hazard involved in apparatus of this type.

The nature of the invention will be readily understood from the following description when read in connection with the accompanying drawings, and the novel features will be particularly pointed out in the appended claims.

In the drawings,

Figure 1 is a plan view of a picker installation embodying features of this invention;

Fig. 2 is a side elevation of the installation shown in Fig. 1;

Fig. 3 is a perspective view of an air filter constructed in accordance with this invention; and

Fig. 4 is a vertical, sectional view through the upper edge of the filter shown in Fig. 3.

Fig. 1 illustrates diagrammatically two single process picker systems A and B of a well known type, arranged in parallel, and both fed with cotton automatically by a Morton conveyor 2. The cotton is delivered to the conveyor pneumatically from the opening room, as is common in mill practice, incoming cotton being conveyed through a wind trunk 3. It is separated from the

conveying air current by means of a condenser 4 at the end of said trunk and the cotton drops by gravity from the condenser on to the conveyor belt 2. Some features of the conveying means just described are better illustrated in Fig. 2. Since this arrangement is common in the textile industry, no detailed description of it is necessary.

Referring to Fig. 2, it will be seen that the picker system there shown comprises a supply hopper 5 provided with the usual mechanism for feeding the cotton automatically from this hopper to the beater section 6 of the breaker unit, and a condenser section 7 which takes the cotton from the beater and discharges it through feed rolls 8 to an intermediate hopper feeder 9. The latter feeder, in turn, delivers the cotton to the beater section 10 of a finisher lapper which also includes a condenser section 12 and a lapper head or calender head 14 for winding the picked web of cotton into the form of a lap. This system may be constructed, arranged and operated like that shown in my pending application Serial No. 363,586.

As is well understood by those skilled in this art, cotton is carried away from a beater by a current of air created by a suction blower, this air current delivering the cotton to the condenser where it is taken out of the air stream or separated from it. Referring to the beater unit 6 shown in Fig. 2, one of the gratings through which the air flows into the beater 6 is shown at 15, and the suction blower for creating the current of air utilized in the beater 6 and condenser 7 is illustrated in dotted lines at 16, this blower being mounted on a shaft 17 which is belted to the beater shaft in the customary manner. Essentially the same construction is included in the finisher section in connection with the beater 10 and condenser 12.

The entire arrangement so far described may be like that commonly used heretofore.

The air discharged by the blowers carries with it considerable dust and some cotton fiber, most of the fiber being very short, and it has been customary heretofore, as above stated, to deliver this air to a dust room from which the air finds its way into the atmosphere outside the mill. According to the present invention, however, the air discharged by the blowers is filtered and again returned to the picker room so that its moisture and heat content both are conserved.

Referring again to Figs. 1 and 2 it will be seen that a conduit or wind trunk 20 conveys the air

from the blower 16, under the floor of the picker room, to a filter 21 located at some convenient point in said room. The corresponding blower for the system B may also be connected in a 5 similar manner to the filter 21, as indicated in Fig. 1. As shown, the blowers for the condensers 12 of the two systems are connected by conduits 22 and 23 to two independent filters 24 and 25, respectively. Consequently, the air used 10 in the beaters and condensers of both systems, while taken from the picker room in the customary manner is returned directly to the picker room again with its heat and moisture content substantially unchanged except for the desirable 15 loss of moisture to the cotton conveyed by the air.

Essentially the same arrangement may be used with the pneumatic conveyor which carries the cotton from the opening room to the 20 picker room. In fact, where the mill arrangement permits, the opening room and picker room may be so tied together from a standpoint of temperature and humidity conditions and air circulation that they may be regarded as a single 25 room, essentially the same temperature and humidity being desirable in both. Where such an arrangement is used, air taken from the picker room may be discharged into the opening room, and vice versa, suitable provision being 30 made for permitting the desired circulation of air between the two rooms. A proper degree of humidification may be maintained by any of the systems commonly used in this industry.

35 The provision of a filter which will satisfy the requirements of a system of this character has proved to be an exceptionally difficult problem. Pneumatic separators such as those commonly used in a great variety of industries have not 40 proved satisfactory in separating the finely divided particles of dust and fiber from the air stream discharged by the condenser blowers. It seems evident, therefore, that some type of filter must be used as distinguished from centrifugal separators of the character at present 45 available. Moreover, such a filter must be highly effective, while at the same time permitting a relatively free passage of the great volume of air therethrough so as to avoid any substantial increase 50 in the power required to drive the blowers. The filter construction illustrated in Figs. 3 and 4 has been developed after a long series of experiments and has been found to satisfy the requirements above mentioned.

55 Important features of this filter reside in the arrangement of the screens, the peculiar structure of the layer of fibrous material deposited between them, and the manner in which this fibrous deposit is built up. The particular filter 60 shown in Fig. 3 consists of five panels *a*, *b*, *c*, *d* and *e*, each including a frame, and all of these frames being secured together on an angle iron frame to form a box-like structure. Each panel in the embodiment of the invention illustrated 65 in Figs. 3 and 4, includes an inner screen 27 and a second or outer screen section 28 spaced from the first screen by a relatively short distance, say for example, one-quarter of an inch. The inner may consist of wire screening of very 70 coarse mesh, the meshes being, say, one-quarter of an inch or one-half an inch square, while the outer screen is much finer and has, for example, forty or fifty meshes to the inch. These screens perform very little, although an important 75 part, of the filtering operation, but they

hold between them a layer of fiber which is taken out of the air stream flowing through the filter and which performs most of the filtering action.

When the filter is first installed and is started into operation, the current of air laden with fine 5 dust and with some scattering or residual fiber flows very freely through the screens and some of the fine dust passes through with it. The fiber passes freely through the inner screen 27, but practically all of it is stopped by the second 10 screen 28. It is held against the latter screen by the action of the current of air in which it has been delivered. Additional fiber is deposited in this manner, some of the fibers wrapping around the wires of the coarse inner screen 27, 15 while others pass freely through the meshes of the screen and are caught either by the second screen or by the layer of fiber previously deposited on it, until finally the entire space between the two screens is filled with fiber deposited 20 in this manner. This fiber forms a filter sheet which is highly pervious to air but which is extremely effective in catching and holding additional fibers and the fine particles of dust carried by the air stream. Consequently, while the 25 filtering action is somewhat faulty when the apparatus is first started into operation, in a very few minutes a filter sheet is built up in the manner above described between the screens and thereafter the filtering action is highly satisfactory, it being understood that it is not necessary 30 to have the entire space between the two screens completely filled with fiber in order to filter the air properly for present purposes.

When the machinery is stopped at noon and again at night, the blowers, of course, are stopped and consequently, the pressure of the air which has held the fiber distributed over the surface of the inner screen is relieved. This fiber, therefore, and the dirt held in it simply fall away from the inner screen by gravity and drop to the bottom of the box. Consequently, the filter cleans itself due to the interruption in air flow. The filter sheet between the screens, however, is held in place by them against the action of gravity 45 so that when the machinery is again started up an entirely satisfactory filtering action is maintained.

Such a filter may be operated for several days without attention, but after a time the layer of fiber 50 between the screens becomes so loaded with fine dust that an undesirable degree of back pressure is created. The screen panels should then be disconnected from the angle iron frame and the inner section 27 of each section should 55 be separated from the outer section 28 and the layer of fiber 50 completely removed. This operation is facilitated by mounting both screens on separate frame sections and securing them together by hinges, screws, or the like, before they are fastened to the angle iron frame by the bolts 31. When the filter has been reassembled 60 it is then ready to be started into operation again in the manner above described.

It is desirable, also, to hinge one of the panels 65 of the filter shown in Fig. 3, as for example the panel *d*, and to provide a simple form of latch, such as that shown at 32, Fig. 3, for holding it closed so that this panel can be swung into an open position when the filter is not being used to 70 permit the removal of the accumulation which drops down to the bottom of the box.

This invention thus makes it entirely feasible to humidify opening and picking rooms and reduces the heat losses which have heretofore been 75

a substantial item in the cost of operating these departments of a mill located in cool climates. At the same time the expense involved in equipping opening and picking rooms in accordance with this invention is held within entirely reasonable limits. It has further been demonstrated that this arrangement provides an effective means for controlling fire which originates in the beater and is carried through into the filter. The fine 10 mesh screen of the filter effectually prevents the flame from passing through it so that while smoke will come into the picker room, the flame will be entirely confined to the interior of the filter where it can easily be extinguished. Since all 15 of the parts of the filter are made of metal there is nothing inside the filter structure to support combustion except the materials strained out of the air. The invention, therefore, substantially reduces the fire hazard involved in the handling of 20 the dust and the fine fiber discharged from the condensers.

As shown in Figs. 3 and 4, the screening surface is not continuous but is interrupted by non-screening upright connecting members at the 25 four corners of the screen structure. This arrangement has proved to be an advantage in causing the filter to clean itself automatically whenever the blowers are shut down. In other words, it has been found that if these non-screening areas in the corners are omitted or are made 30 extremely narrow so that they are, in effect, omitted, the solid particles of fiber and dust filtered out of the air stream and which accumulate on the inner surface of the filter sheet will, 35 after a long period of operation, build up a continuous hollow structure composed of fiber and dust which may, under some circumstances, become self-sustaining. However, the non-screening sections at the corners of the filter structure, 40 as illustrated in the drawings, interrupt the continuity of the fibrous filter cake that collects on the inner surface of the filter and prevents it from becoming self-sustaining. Consequently, and since these accumulations require the pressure 45 of the air screen on them to hold them against the filter sheet, they fall away from this sheet by gravity whenever the blowers are shut down and the air stream, as a result, is stopped. Such an arrangement, therefore, materially reduces the 50 care and attention which otherwise would have to be given to the filter.

While I have herein shown and described a typical installation embodying this invention, it will be evident that the invention is susceptible 55 of embodiment in a variety of other forms. Also, that while the invention has been particularly described with reference to the requirements of cotton machinery, it can also be used to advantage in the handling of other fibers. Consequently, the terms "cotton" or "cotton fiber" as 60 herein employed are used in a generic sense to include other fibers which can be handled in essentially the same manner.

Having thus described my invention, what I 65 desire to claim as new is:

1. That improvement in methods of picking cotton which consists in beating the cotton, warming and humidifying the air in the picker room, conveying the cotton from the beater in 70 a stream of said air taken from the picker room, condensing the cotton and thereby separating it from said air stream, filtering the air stream subsequent to said separation, and returning the filtered air to said picker room with its heat and 75 moisture content substantially unchanged ex-

cept for the loss of moisture to the cotton so handled.

2. In a system of the character described, the combination with a beater and means for feeding cotton to said beater, of means for conveying 5 the cotton away from said beater in a current of air, a condenser for separating most of the cotton from said air stream, and a filter into which the dust and fiber remaining in the air after it passes through said condenser is discharged, said filter being constructed to utilize 10 said remaining fiber in filtering said air stream and to confine within itself any fire started in or carried into the filter.

3. In a system of the character described, the 15 combination with a beater and means for feeding cotton to said beater, of means for conveying the cotton away from said beater in a current of air, a condenser for separating practically all 20 of the cotton from said air stream, means for conducting the air discharged from said condenser externally of the machine, and metallic means interposed in the passage through which said air stream is conducted for limiting the 25 progress of a fire in the air stream so conducted.

4. In a system of the character described, the combination with a beater and means for feeding cotton to said beater, of means for conveying the cotton away from said beater in a current of air, a condenser for separating practically all 30 of the cotton from said current of air, and a filter structure comprising a metallic means for filtering the air discharged from said condenser and returning it again to the room in which said 35 system is located, said filtering means being interposed in the passage through which said current of air is conducted and arranged to stop the progress along said current of air of any fire started in the material carried by the air so discharged.

5. In a system of the character described, the combination with mechanism for operating on a body of cotton to work it into a different form or condition, of means for conveying the cotton fiber in a stream of air, apparatus for separating 45 practically all of the cotton in said air stream from the air and the dust conveyed by said stream, and a filter structure comprising metallic means through which said air stream is conducted subsequently to its separation from the 50 cotton and which is constructed to utilize the residual fiber in said air stream to build up a highly pervious, fibrous, filter sheet serving to remove the dust from the air stream, said filter structure and the air conveying means associated therewith being arranged to re-circulate 55 the air so filtered for use again in conveying additional cotton, whereby the heat and moisture content of said air stream will be conserved.

6. In a system of the character described, the 60 combination with mechanism for operating on a body of cotton to work it into a different form or condition, of means for conveying the cotton fiber in a stream of air, apparatus for separating 65 practically all of the cotton in said air stream from the air and the dust conveyed by said stream, and a filter structure comprising metallic means through which said air stream is conducted subsequently to its separation from the cotton and which is constructed to utilize the 70 residual fiber in said air stream to build up a highly pervious, fibrous, filter sheet serving to remove the dust from the air stream and so disposed that the pressure of said air stream is required to hold the accumulation of filtered solids 75

against said sheet and such accumulations will fall away from said sheet by gravity whenever the air flow stops, said filter structure and the air conveying means associated therewith being arranged to re-circulate the air so filtered for use again in conveying additional cotton, whereby the heat and moisture content of said air stream will be conserved.

7. In a cotton picking system, the combination 10 with a plurality of picking units each including a beater and a condenser associated with it, of one or more air filters comprising metallic means each adapted to confine within itself any fire started in or carried into it, conduits for conducting the air discharged from said condensers into the said filter or filters, and externally of the machine, and means for creating a continuous circulation of air through said beaters, condensers and filter and returning the air to the 20 picker room after it has been filtered.

8. In a system of the character described, the combination with a beater unit for operating on a stream of cotton fed into it and a condenser associated with said beater, of a filter structure 25 comprising a metallic means, means for creating

a flow of air through said beater, condenser and filter, suitable conduits associated with said elements and said means to convey the air from said condenser to said filter and to produce a re-circulation of the filtered air through the system, said filter being constructed to utilize the residual fiber in said air stream to build up a highly pervious, fibrous filter sheet serving to remove the dust from the air stream and to maintain said sheet of an approximately constant thickness notwithstanding the removal therefrom of accumulations of material filtered out of said air stream.

9. That improvement in methods of picking cotton which consists in beating the cotton and working it into a well opened fluffy condition, humidifying the air in a substantially closed picker room, conveying the cotton so prepared in a stream of humidified air taken from the picker room, condensing the cotton and thereby separating it from said air stream, filtering the entire air stream used in the conveying and condensing operation, and returning the filtered air again to the picker room.

ROBERT S. CURLEY.
